HARRY S. VINCENT, OF RIDGEWOOD, NEW JERSEY, AND JOHN L. MOHUN, OF BROOKLYN, NEW YORK.

LOCOMOTIVE-DRIFTING-VALVE MECHANISM.

1,211,646.

Specification of Letters Patent.

Patented Jan. 9, 1917.

Application filed August 19, 1916. Serial No. 115,782.

To all whom it may concern:

Be it known that we, HARRY S. VINCENT, of Ridgewood, in the county of Bergen and State of New Jersey, and JOHN L. MOHUN, 5 of the borough of Brooklyn, in the county of Kings and State of New York, have jointly invented a certain new and useful Improvement in Locomotive-Drifting-Valve Mechanisms, of which improvement the following is a specification.

Our invention relates to valve mechanism for automatically effecting the admission of a limited quantity of steam, directly from the boiler to the valve chests and cylinders of a 15 locomotive engine, during the periods in which the locomotive is "drifting", or running with its throttle valve closed, in order to prevent the formation of a vacuum in the cylinders, to afford proper lubrication to the 20 cylinders, and to prevent the carbonization of oil therein.

In a separate application for Letters Patent filed by us of even date herewith, Ser. No. 115781, we have set forth a drifting 25 valve mechanism of the type above specified, the leading and characteristic feature of which consists in a valve which controls the supply of a limited quantity of steam to a distribution valve chest and cylinder of a locomotive, when running with its throttle closed and which is alternately opened and closed by positive connection with a moving member of a locomotive, and means, interposed between said valve and cylinder, for 30 alternately effecting the admission of steam to, and its exclusion from, the cylinder. Our present invention likewise embodies this 35 feature, and its object is to provide a drifting valve mechanism which will attain the advantages of that of our application Ser. No. 115781 aforesaid, as well as that of rendering the major portion of the mechanism 40 inoperative when the locomotive is working under normal conditions, in order to reduce 45 wear to a minimum.

The improvement claimed is hereinafter fully set forth.

In the accompanying drawings: Figure 1 is a side view, in elevation, of the forward 50 portion of a locomotive engine, illustrating an application of our invention; Fig. 2, a front view, partly in section, of the same; Fig. 2^a, a longitudinal section, through an intercepting reservoir; Fig. 3, a view, partly 55 in elevation and partly in vertical central

section, of a drifting valve casing; and its accessories; Figs. 4 and 5, transverse sections, on the lines *a a* and *b b*, respectively, of Fig. 3; Fig. 6, a vertical section through a drifting valve casing, illustrating a structural modification, on the line *c c* of Fig. 7; Fig. 7, a similar section, on the line *d d* of Fig. 6; Fig. 8, a similar section, on the line *e e* of Fig. 7; Fig. 9, a horizontal section, on the line *f f* of Fig. 7; Fig. 10, a front view, 60 in elevation, of the operating arm and gear connections; Fig. 11, a view, half in front elevation and half in vertical section on the line *g g* of Fig. 12, through a drifting valve casing, illustrating a further structural 65 modification; Fig. 12, a vertical section through the same, on the line *h h* of Fig. 11; Fig. 13, a transverse section, on the line *i i* of Fig. 4, showing the bearing 18^b; and, Fig. 14, an axial section through the shut off 70 valve casing.

In the practice of our invention, referring descriptively to the specific embodiment thereof which is exemplified in Figs. 1 to 5 inclusive, two intercepting reservoirs, 14, are 75 provided, one of said reservoirs and one drifting valve chest, 1, for each of the distribution valve chests, 2, of the locomotive, which communicate by ports (not shown) 80 with the cylinders, 13, in the usual manner. The intercepting reservoirs and the drifting 85 valve chests, and their connections and contained mechanism, being similar, in all particulars of construction and operation, the description of those located on one side of the locomotive will be understood as being 90 equally applicable to those on the other side.

An intercepting reservoir, 14, and a drifting 95 valve casing, 1, are located in any convenient position adjacent to one of the distribution valve chests, 2, both being, in this instance, shown as connected to and supported by a vertical bracket, 15, secured to a flange on the valve stem guide, 2^a. The intercepting reservoir, 14, which is of cylindrical form, is divided, by a transverse partition, 14^a, into two separate chambers, 14^b and 14^c, which are connected by pipes, 14^{bb} and 14^{cc}, respectively, with the upper horizontal portion of the drifting valve casing, 1, 100 which is of T form. Drifting valves, 7, which, in this instance, are of the piston type, are fitted in bushings, 1^a, in the upper horizontal portion of the drifting valve casing, the ends of which are closed by remov- 110

able heads, 1^m, said pistons being connected by an integral intermediate bridge piece, 7^a, and the lower end of the casing is closed by a removable head, 1^r. Saturated steam from the boiler is supplied to the casing through a drifting valve supply pipe, 9, leading into a longitudinal passage, 1^k, formed on the upper horizontal portion of the casing, the ends of which passage open into annular 10 passages, 1^{kk}, in the upper portion of the casing, adjacent to its ends.

The purpose of the intercepting reservoir, 14, is, as in the construction of our application Ser. No. 115,781, to measure out from each of its chambers, a definite quantity of steam for delivery to the adjacent engine cylinder, the drifting valve operating so that one chamber of each reservoir is in communication with the cylinder at any given time, and, when in such communication, not communicating with the steam supply.

The drifting valve supply pipes of the casings on both sides of the locomotive, lead 25 to the casing, 10, of an automatic shut off valve, from which casing a pipe, 9^b, controlled by a manually operated angle valve, 9^a, which is open continuously during the operation of the locomotive, leads to the 30 steam space of the locomotive boiler, 11. The shut off valve casing, 10, incloses a differential piston valve mechanism by which the admission of saturated steam through the pipe, 9^b, to the drifting valve supply 35 pipes, is automatically effected and maintained whenever, and so long as, the throttle valve of the locomotive is and remains closed, and is cut off whenever, and as long as, said valve is and remains opened. It 40 will, of course, be understood that the admission of steam to the superheater header, 12, with which the shut off valve communicates, and which communicates with the main steam supply pipe, 12^a, and the outside 45 steam pipes, 4, is controlled by a throttle valve, in the ordinary manner. The shut off valve mechanism, which is illustrated in Fig. 14, does, in and of itself not form part of our present invention, and being, more 50 over, fully described and shown in our application Ser. No. 115781 aforesaid, it will not be herein in detail set forth.

The drifting valve supply pipe, 9, communicates through the passages, 1^k and 1^{kk}, and through ports, 1^t, in the bushings, 1^e, with the interior of said bushings, and communication is established between the interior of the bushings and the pipes, 14^{bb} and 14^{cc}, leading to the chambers of the intercepting reservoir, 14, through ports, 1^t, formed in the bushings, when said ports are opened by the drifting valves. A drifting delivery steam pipe, 3, leads from the space within the casing, 1, between the drifting valves, 7, into the distribution valve chest,

through a connection with the outside steam pipe, 4, which supplies said chest.

Reciprocating movement is imparted to the drifting valves, for controlling the ports, 1^t, by a vibratory operating shaft, 17, which 70 is journaled in bearings in the lower portion of the casing, and carries an arm, 16, having, on its upper end, a cylindrical bearing, 16^a, engaging a recess, 7^b, at the middle of the length of the bridge piece, 7^a, which 75 connects the drifting valves. A set screw, 7^c, engaging the casing, 1, and entering a longitudinal groove in the bridge piece, prevents the drifting valves from turning in the bushings. Springs, 7^e, interposed 80 between the drifting valves and the casing heads, 1^m, serve to return the drifting valves to the normal central position shown in Fig. 3, when they are not in operation, and drain pipes, 1^h and 1ⁱ, lead from the casing to suitable points of discharge. 85

A special novel and advantageous feature of our invention consists in means for rendering the major portion of the mechanism inoperative when the locomotive is working 90 under normal conditions, *i. e.*, running with open throttle, and thereby reducing wear to a minimum. To this end, the operating shaft is provided with an automatically operable clutch mechanism which will now be 95 described. The operating shaft, 17, carries on one of its ends, a clutch collar, 17^a, which engages an adjoining clutch socket, 18^a, formed on the upper end of an arm, 18, and fitted freely on the operating shaft, adjacent 100 to a bearing, 19^a, on a bracket, 19, bolted to the drifting valve case, the outer end of the operating shaft being journaled in said bearing. Longitudinal movement of the clutch socket and arm, 18, relatively to the 105 operating shaft, is prevented by a segmental bearing, 18^b, on the clutch socket, which abuts against a projection on the bracket, 19. The opposite end of the operating shaft carries a piston, 20, fitted in a casing, 1^p, which 110 projects laterally from the drifting valve casing, 1, and is closed, at its outer end, by a removable head, 1^r. A spring, 21, is fitted in a case, 21^a, which enters the casing, 1^p, and is secured thereto by the head, 1^r, said 115 spring bearing on the outer side of the piston, 20, and acting to maintain the clutch sections, 17^a and 18^a, in engagement during the periods in which the locomotive is drifting. A port, 1^s, leads from the casing 1^p, 120 on the inner side of the piston, 20, to the interior of the casing, 1, within which it is continuously open to the distribution valve chest, 2, through the drifting delivery steam pipe, 3. Vibratory movement is imparted to 125 the arm, 18, and, through said arm, to the operating shaft, 17, when the locomotive is drifting, by a connection with a moving member of the locomotive. In the instance shown, the arm, 18, is coupled to the lower 130

pin, 22^a, of the combination lever, 22, of the valve gear, by links, 22^b and 22^c.

In the operation of a locomotive on which the invention is applied, saturated steam is supplied by the automatic operation of the shut off valve, to the drifting valve supply pipes, 9, immediately upon the closure of the throttle valve and the consequent "drifting" operation of the locomotive. The steam passes through the pipes, 9; enters each of the drifting valve casings on the outer sides of the piston valves, 7, 7, thereof; and by the reciprocation of said valves, effected by the connections described, is admitted, alternately, through the passages, 1^b and 1^c, ports, 1^d, and pipes, 14^{bb} and 14^{cc}, to one and the other of the chambers, 14^b and 14^c, of the intercepting reservoir, 14, connected with the drifting valve casing. From said chambers, it passes, through the ports, 1^d, the interior of the casing, and the drifting delivery steam pipe, 3, to the adjacent distribution valve chest, 2. The admission of saturated steam thus effected, continues throughout the period in which the locomotive is drifting, and as soon as the throttle is reopened for normal operation, it is terminated by the closure of the drifting supply pipes by the automatic operation of the shut off valve. The movement of the drifting valve pistons is also stopped, upon the closure of the throttle, by the disengagement of the clutch members of the operating shaft as described, and the drifting valve pistons are brought to their middle positions by the springs, 7^e. When the locomotive is standing, no saturated steam will be admitted to the distribution valve chests, by reason of the drifting valves being stationary, in position to intercept communication between the pipes, 9 and 3, and consequently to prevent the passage of steam through the drifting valve casings.

Figs. 6 to 10 inclusive illustrate a structural modification, the operation of which is similar to that of the construction first described, but in which the drifting valves are four in number, and are of the puppet type, and two coincidentally movable operating shafts are applied. Each of the drifting valve casings, 1, is divided by a transverse partition, 1^a, into an upper chamber, 1^b, and a lower chamber, 1^c, which communicate, respectively, through pipes, 14^{bb} and 14^{cc}, with the chambers, 14^a and 14^b, of the intercepting reservoir, 14. Two inlet chambers, 1^d, and two opposite outlet chambers, 1^e, are formed on the casing, the inlet chambers communicating with the drifting valve supply pipe, 9, through a passage, 1^f, and the outlet chambers communicating with the drifting delivery steam pipe, 3, through a passage, 1^g. The inlet chambers, 1^d, communicate with the casing chambers, 1^b and 1^c, through openings controlled by

drifting supply valves, 7^a, of the puppet type, and the outlet chambers, 1^e, communicate with the casing chambers, 1^b and 1^c, through openings controlled by drifting delivery valves, 7^b, similar to the drifting supply valves. The stems of the supply and delivery valves carry pistons, 7^c, working in bushings, 1^d, fitted in the inlet and outlet chambers, the outer ends of which are closed by removable heads, 1^e. Springs, 7^f, are interposed between the pistons, and the heads of the chambers, to effect the seating of the valves, and to insure the seating of the valves, 7^b, of the outlet chambers, their pistons are subject to pressure from the chambers, 1^b and 1^c, of the casing, through ports, 1^d, leading from said chambers to the outer sides of the pistons, as shown in Fig. 9.

A vibratory operating shaft, 17, journaled in the lower portion of the casing, 1, carries an arm, 17^a, which projects downward between, and is adapted to alternately unseat, the lower supply valve, 7^a, and the opposite delivery valve, 7^b. A segment gear, 17^b, fixed on the operating shaft, engages a similar gear, 28^a, on a secondary operating shaft, 28, which is journaled in the casing, above and parallel with the shaft, 17, and has secured upon it, an arm, 28^b, which projects upwardly between, and is adapted to alternately actuate, the upper supply valve, 7^a, and the opposite delivery valve, 7^b. It will be seen that by this construction, a supply valve and a delivery valve are coincidentally opened, to admit steam to one of the chambers of the intercepting reservoir, and deliver it from the other, by the movement of the operating shaft, 17, in one direction, and a supply valve and a delivery valve are coincidentally opened for a similar purpose.

The drifting valves are rendered inactive during the periods that the locomotive is running under normal conditions, by clutch mechanism similar to that shown in Figs. 3 and 4, and previously described. The arm, 18, which is freely mounted on the operating shaft, and through which motion is imparted thereto, carries a clutch socket, 18^a, which engages a clutch collar, 17^b, on the operating shaft, which is moved in its bearings in one direction, to engage the clutch collar and clutch socket, by a spring, 21, when the throttle is closed, and is moved in the opposite direction, to disengage the collar and socket, when the throttle is opened, by pressure from the distribution valve chest, acting through a port, 1^f, on a piston, 20, secured on the operating shaft.

The operation of the modified form of the appliance last above described is similar to that of the construction first described, the admission of saturated steam, through interposed intercepting reservoirs, to the distribution valve chests, during the period of drifting, being effected by the movements

of the drifting valves, and the drifting valves being rendered inoperative by similar mechanism, when the locomotive is running with open throttle.

- 5 A further structural modification of the invention in which the drifting valves are of the oscillatory slide type, is illustrated in Figs. 11 and 12. The drifting valve casing is, in this modification, formed in two 10 sections, 1 and 1^{aa}, which are connected by bolts, 1^{bb}. The inner end wall, 1^{hh}, of the section, 1^{aa}, forms a partition between the sections and the section, 1^{aa}, is divided by a horizontal wall, 1^l, shown in dotted lines in 15 Fig. 11, into an upper chamber, 1^{cc}, and a lower chamber, 1^{dd}. The drifting valve supply pipe, 9, leads into the chamber, 1^{cc}, and the drifting delivery steam pipe, 3, leads out of the chamber, 1^{dd}. The casing 20 section, 1, is divided into two chambers, 1^{cc}, which are located side by side; are of similar form and dimensions; and are connected by pipes, 14^{bb} and 14^{cc}, with the chambers of the intercepting reservoir, 14. 25 Ports, 1^l, shown in dotted lines in Fig. 11, are formed in the wall, 1^{hh}, which separates the chambers, 1^{cc} and 1^{dd}, of the casing section, 1^{aa}, from the chambers, 1^{ee}, of the section, 1, and communication between the 30 chambers, 1^{cc} and 1^{dd}, and the chambers, 1^{ee}, is controlled by drifting valves, 24, of the oscillatory slide type, one of which is fitted in each of the chambers, 1^{ee}, and which are provided with ports, 24^a, adapted to register, in certain positions of the valves, with the wall ports, 1^l. The drifting valves, 24, are held to their seats on the wall, 1^{hh}, by a spring, 24^b, and are secured, respectively, on a preliminary operating shaft, 17, and a 40 secondary operating shaft, 23, which are journaled in bearings in the wall, 1^{hh}, and in the opposite wall of the casing section, 1, and extend outwardly, through suitable stuffing boxes in the latter wall. 45 The drifting valves and their operating shafts are adapted to be rendered inoperative when the locomotive is running with open throttle, by clutch mechanism, which is similar to that before described, and which will not therefore be again set forth in full detail. The preliminary operating shaft, 17, is vibrated by an arm, 18, connected with a reciprocating member of the locomotive, and is coupled, by a link, 18^b, with an arm, 23^a, on the secondary operating shaft, 23. The arms, 18 and 23^a, are fitted freely on the respective shafts, and carry clutch collars, 18^c and 23^c, respectively, engaging clutch sockets, 17^a fixed on the 55 shafts. The inner ends of the shafts carry pistons, 20, which are acted upon by pressure from the distribution valve chests, through ports, 1^l, leading out of the chambers, 1^{dd}, when the locomotive is running 60 with open throttle, to move the shafts, 17 65 with

and 23, longitudinally, and thereby disengage the clutch members and stop the movement of the shafts and valves. Upon the closure of the throttle, pressure on the pistons, 20, is released, and the shafts are 70 moved longitudinally to reengage the clutch members and reinstate the movements of the shafts and drifting valves.

The operation of the modification shown in Figs. 11 and 12, is similar to that of the 75 constructions shown in the preceding figures, and before described. Saturated steam is continuously admitted, while drifting, to the upper chamber, 1^{cc}, of the casing section, 1^{aa}, and thence, alternately, to one 80 and the other of the chambers, 1^{ee}, of the section, 1, from which it passes to the chambers of the intercepting reservoir, 14. From these it is delivered, by the movements of the drifting valves, to the lower chamber, 85 1^{dd}, and thence passes, through the drifting delivery steam pipe, 3, to the distribution valve chests.

We claim as our invention and desire to 90 secure by Letters Patent:

1. In a drifting valve mechanism for locomotives, the combination of a valve controlling the admission of steam to a locomotive cylinder, of a throttle governed supply pipe; means for actuating said valve by 95 positive connections to a moving member of a locomotive; and automatically operative means for disconnecting said valve and moving member, during the periods in which the locomotive is running under the normal 100 condition of steam admission through the supply pipe.

2. In a drifting valve mechanism for locomotives, the combination of a valve controlling the admission of steam to a locomotive cylinder, of a throttle governed supply pipe; means for actuating said valve by positive connections to a moving member of a locomotive; and automatically operative means for disconnecting said valve and 105 moving member, upon and by the opening of the throttle valve of the supply pipe.

3. In a drifting valve mechanism for locomotives, the combination of a valve controlling the admission of steam to a locomotive cylinder, of a throttle governed supply pipe; means for actuating said valve by 115 positive connections to a moving member of a locomotive; and automatically operable means for disconnecting said valve and moving member, upon and by the opening of the throttle valve of the supply pipe and reinstating its operation, upon and by the closure of said valve.

4. In a drifting valve mechanism for locomotives, the combination of a valve controlling the admission of steam to a locomotive cylinder, independently of a throttle governed supply pipe; means for actuating said valve by a moving member of a locomotive; 125 130

- and automatically operative clutch mechanism for engaging said valve with, and disengaging it from, its actuating means, upon and by the closure and opening, respectively, 5 of the throttle valve of the supply pipe.
5. In a drifting valve mechanism for locomotives, the combination of a valve controlling the admission of steam to a locomotive cylinder, independently of a throttle governed supply pipe; means for actuating said valve by a moving member of a locomotive; a clutch mechanism interposed between said valve and its actuating mechanism; a piston which is actuated by cylinder pressure to 10 effect the disengagement of the clutch members, upon the opening of the throttle valve of the supply pipe; and a spring by which the clutch members are engaged, upon the closure of said valve.
- 20 6. In a drifting valve mechanism for locomotives, the combination of a double chambered intercepting reservoir; an independent drifting valve casing communicating therewith, with the steam space of a locomotive boiler, and with a locomotive cylinder; two drifting valves fitted in said casing, each controlling communication, alternately, between the locomotive boiler and one of the chambers of the intercepting reservoir 25 and between said chamber and the cylinder; and means for actuating said valves by a moving member of a locomotive.
7. In a drifting valve mechanism for locomotives, the combination of a double chambered intercepting reservoir; an independent drifting valve casing communicating therewith, with the steam space of a locomotive boiler, and with a locomotive cylinder; two drifting valves fitted in said casing, each 30 controlling communication, alternately, between the locomotive boiler and one of the chambers of the intercepting reservoir and between said chamber and the cylinder; and connections coupling said valves to a moving member of the distribution valve gear of the locomotive.
- 40 8. In a drifting valve mechanism for locomotives, the combination of a double chambered intercepting reservoir; an independent drifting valve casing communicating therewith, with the steam space of a locomotive boiler, and with a locomotive cylinder; two drifting valves fitted in said casing, each 45 controlling communication, alternately, between the locomotive boiler and one of the chambers of the intercepting reservoir and between said chamber and the cylinder; and means for actuating said valves by a moving
- member of a locomotive; and means for rendering said valves inoperative during the 60 periods in which the locomotive is running under the normal condition of steam admission through the supply pipe.
9. In a drifting valve mechanism for locomotives, the combination of a drifting valve casing, communicating, adjacent to its ends, with connections, each leading to an intercepting reservoir chamber, and communicating, intermediate thereof, with a connection leading to a locomotive cylinder; a 70 boiler steam supply pipe; two connected drifting valves, fitted to reciprocate in the casing, each controlling communication, alternately, between the boiler steam supply pipe and one of the reservoir chamber connections, 75 and between said connection and the cylinder connection; a vibratory operating shaft journaled in the casing; an arm connected to said shaft and coupled to the drifting valves; and means for imparting oscillatory movement to the operating shaft from a moving member of the locomotive.
10. In a drifting valve mechanism for locomotives, the combination of a drifting valve casing, communicating, at its ends with 80 connections, each leading to an intercepting reservoir chamber, and communicating, intermediate thereof, with a connection leading to a locomotive cylinder; a boiler steam supply pipe; two connected drifting valves 85 fitted to reciprocate in the casing, each controlling communication, alternately, between the boiler steam supply pipe and one of the reservoir chamber connections and between said connection and the cylinder connection; a vibratory operating shaft, journaled, with the capacity of longitudinal movement, in the casing; an arm connected to said shaft and coupled to the drifting valves; an operating arm fitted freely on 90 said shaft and adapted for connection to a moving member of the locomotive; a clutch member fixed on said arm; a clutch member fixed on the operating shaft and adapted to engage the clutch member of the operating 95 arm; a piston fixed on the operating shaft; a port leading from the cylinder connection of the casing to one side of said piston; and a spring bearing on the opposite side of said piston.
